United States Patent Office

Des. 202,720
Patented Nov. 2, 1965

202,720

COMBINED CONTAINER AND COVER THEREFOR

Jan Nathan Ostborg, Lombard, and Robert Boleslaw Lurski, Chicago, Ill., assignors to Club Aluminum Products Company, La Grange Park, Ill., a corporation of Illinois

Filed Mar. 18, 1965, Ser. No. 84,351

Term of patent 14 years

(Cl. D44—15)

Fig. 1

FIGURE 1 is a perspective view of a combined container and cover therefor, showing our new design, a portion being broken away for ease of illustration;

FIG. 2 is an elevational view thereof;

FIG. 3 is an elevational view taken at right angles to the showing of FIG. 2;

FIG. 4 is a top plan view thereof on a reduced scale; and

FIG. 5 is a bottom plan view thereof on the same scale as FIG. 4.

We claim:

The ornamental design for a combined container and cover therefor, substantially as shown and described.
